UNITED STATES PATENT OFFICE.

WILLIAM F. NIEBLING, OF CINCINNATI, OHIO.

ICE-DUMP.

SPECIFICATION forming part of Letters Patent No. 593,680, dated November 16, 1897.

Application filed March 19, 1897. Serial No. 628,281. (No model.)

To all whom it may concern:

Be it known that I, WILLIAM F. NIEBLING, a citizen of the United States, and a resident of Cincinnati, Hamilton county, State of Ohio, have invented certain new and useful Improvements in Ice-Dumps; and I do declare the following to be a clear, full, and exact description of the invention, such as will enable others skilled in the art to which it appertains to make and use the same, attention being called to the accompanying drawings, with the reference-numerals marked thereon, which form a part of this specification.

This invention relates to improvements in ice-dumps, which are devices used in connection with the manufacture of artificial ice. As is well known the water for such purpose is frozen in vessels or tanks, the ice blocks produced assuming then the interior shape of these freezer vessels, filling them out with such a close and tight fit that removal of the ice blocks is not readily accomplished and, in fact, is not possible until the dimensions of the latter have been somewhat reduced by melting. Since these freezers when filled are of considerable weight, ice-dumps have been provided to facilitate their handling, particularly for the purpose of turning them in a manner to permit the ice block to slide out. To accelerate such sliding out, steam or hot water is applied against the outside of the freezer vessels to start the melting of the block in order to loosen it from the walls of the vessel.

My improvements relate particularly to an addition of the means for applying the medium which induces the melting with an object of obtaining quicker results.

They also relate to certain mechanical additions and details of construction, all of which are fully explained in the following specification and claims, which form a full description of the invention, its operation, parts, and construction, which latter are also illustrated in the accompanying drawings, in which—

Figure 1 shows a side elevation of an ice-dump in the act of dumping and provided with the improvements contemplated by my invention. Fig. 2 is a front elevation with parts in section of the same as shown in Fig. 1, but with the freezer vessel removed. Fig. 3 is a sectional view of the lower pipe con-

nexion and taken on a line 3 3 of Fig. 1. Fig. 4 is a sectional detail view of the automatic cock and taken on a line 4 4 of Fig. 2. 55

6 is the body of the dump which receives the freezer vessel 7, in which the water is frozen and is therefore of a size to freely admit such vessel. These latter are mostly oblong, and the body 6 is therefore shaped accordingly, being a box-shaped contrivance with one of its ends and narrower sides removed. From each of the broad sides project trunnion-journals 8, which rest in bearings 9, formed in the upper part of standards 65 10, and whereby the dump is pivotally supported so that it may be readily manipulated. For receiving a freezer vessel the body is swung to a position, as shown in dotted lines in Fig. 1, which permits introduction of the former through the open narrow side at 11. The dump is then swung around in a manner to bring its open end 12 with the open end of the freezer vessel in such a position as to permit the ice block to readily slide out of 70 the open end of the freezer vessel, as may be seen in full lines in Fig. 1, where the ice block is shown as having started to leave vessel 7. The dump is sustained in this position by a sill 13, and which is so located and of such 80 height as to guide the ice block upon a short chute or inclined plane 14. This sill is preferably of wood and is supported on an iron bar 15, which permits ready and independent removal of the sill whenever necessary. 85

After the ice block has been discharged and the empty freezer vessel removed the dump is ready to receive another charged vessel, having first been put again in a position, as shown in dotted lines in Fig. 1. It 90 is preferable to provide means which hold the loosely-supported dump firmly in position while being loaded, and for which purpose a spring-catch 16 is provided, which is so located in a fixed position below the dump as to be 95 within the path of a locking-pin 17, secured to the lower end of the dump, and which pin rides upon the inclined end 18 of the catch and thereby depresses the same until meeting an opening 19 therein and back from the end 100 thereof, whereupon the depressed catch regains its position with the end of pin 17 occupying opening 19, whereby any movement of the apparatus is prevented. When ready for

dumping, the spring-catch is simply depressed, for which purpose a laterally and upwardly projecting tread 21 is provided.

To hasten the loosening of the ice block from within vessel 7 after dumped, steam or hot water is applied from pipes 22, 23, and 24, the ends of which are closed, the discharge being in form of a spray through numerous openings in the side of the pipes. These latter and the discharge-openings in them are so located that from pipe 22 the spray plays over the top and sides of vessel 7, (considering position of parts as shown in Fig. 1.) From pipe 23 its back is reached, and pipe 24 discharges against the bottom. The necessary space for pipes 23 and 24 is obtained by projections upon which vessel 7 rests and which prevent it from resting on these pipes, providing thereby also the necessary space to permit the spray to spread sufficiently to reach fully the particular surfaces. These projections are constructed in form of timbers 25 and 26, the first being in the short end and supporting the vessel when first put in with the position of the dump, as shown in dotted lines in Fig. 1. After dumping—that is, when in position, as shown in Fig. 1 in full lines—the vessel rests on timbers 26. Catches 27 at the outer ends of the latter prevent the vessel from sliding out with the ice. The spray-pipes are supplied from a pipe 28, which divides into branches 29 and 31, the first supplying pipe 22, the other passing through the narrower side or bottom for the time being when in dumping position of body 6 and supplying pipes 23 and 24. An interposed cut-off device controls this supply automatically in this manner, that when body 6 is in position for receiving the supply is cut off, but is turned on as soon as it arrives in position for dumping. This cut-off device consists of a cock, the plug of which is formed by one of the trunnion-journals 8, which is hollow for such purpose, as shown at 32, and with which hollow part pipes 29 and 31 communicate. The housing for the cock is formed by the bearing 9 for the particular journal. Pipe 28 connects to this bearing, passing through it, and cock-journal 8 32 has a port 33, which is so located that when the parts are in position for dumping this port registers and establishes communication with the open end of the pipe 28, as shown in Fig. 2, the hot water passing through bore 32 and into pipes 29 and 31, and before and after this time—that is, while the dump is in position for receiving vessel 7—such communication between bore 32 and pipe 28 is shut off, as shown in Fig. 4. Stuffing-boxes

are provided for the cock at the ends of its bearing to receive suitable packing to prevent leakage, the packing being held in place by glands 34 and 35. The discharge from the pipes may be regulated by valves 36 and 37, and entirely cut off from either the upper or lower branches. The entire discharge is regulated and controlled by valve 38 in pipe 28.

39 is a catch-basin, catching the waste water and drip from the melting ice and the spray. Its upper flange may be used to support the base of standards 10, and the iron bar 15 supporting sill 13.

As will be seen no extra cock nor any devices for operating it are required, its parts being formed by one of the trunnions and by the bearing of the same. While spray-pipes 75 acting against the top and upper side of the freezer vessel have been used before, the application of such pipes against the under side of the vessel is broadly new with me. These latter pipes are, however, very important, and 80 one pipe applied against the bottom of the freezer vessel gives quicker results than any number of pipes applied elsewhere, because the melting is from the bottom and the loosening of the ice block is accelerated by its 85 weight, which causes it to sink into the space created by the melting.

Having described my invention, I claim as new—

1. In an ice-dump, the combination of a 90 body 6 open in a manner to be capable of discharging and receiving a freezer vessel and pivotally supported to permit it of being swung into the necessary position for either purpose, and a heat-conveying pipe 24 being 95 below the freezer vessel and discharging against the under side of it when the parts are in position for dumping.

2. In an ice-dump, the combination of a 100 body 6, open in a manner to be capable of discharging and receiving a freezer vessel and pivotally supported to permit it of being swung into the necessary position for either purpose, timbers 25 upon which the vessel is deposited when put into the dump and timbers 26 which support it while in dumping position and heat-conveying pipes 23 and 24 between the timbers, discharging respectively against its back and under side of the freezer vessel while in position for dumping. 110

In testimony whereof I hereunto affix my signature in presence of two witnesses.

WILLIAM F. NIEBLING.
